MOLDING APPARATUS

James W. Scott, Chicago, Ill., assignor to Western Electric Company, Incorporated, New York, N. Y., a Corporation of New York

Application February 24, 1931. Serial No. 517,704

4 Claims. (Cl. 22—143)

This invention relates to molding apparatus, and more particularly to horizontal type ingot molds for casting copper.

The object of this invention is to provide an improved horizontal type mold by means of which copper ingots may be produced having increased density and workability, electrical conductivity and a minimum of wrinkled and oxidized surfaces.

10 In accordance with the general features of this invention, in one embodiment thereof as applied particularly to the casting of tough pitch or de-oxidized copper in commercial shapes, such as wire bars, cakes or ingots, there is provided a 15 mold comprising a horizontal body member having a mold cavity and depressed cover seating ledges which extend around the inner surfaces of the side and end walls and are inclined downwardly from opposite points adjacent the center 20 of the body member to the ends thereof. Separate covers are held against the ledges, each of which extends from one end of the body to the beginning of the inclined ledge. This leaves a 25 central opening between the adjacent ends of the covers, through which the molten metal may be poured, the top of the opening being above the beginning of the inclined lower surface of the covers which form upper wall portions of the 30 mold cavity, so that any shrinkage of the cast metal will occur in the metal between these two points. This will cause a slight projection at the center of the ingot which may be removed without impairing the strength or quality of the remaining portion of the ingot.

35 According to another embodiment of this invention, the body member is formed with a single continuous depressed cover seating ledge extending around the inner surfaces of the sides and one end wall and inclined downwardly from a 40 point adjacent the opposite end wall. A single cover is held against the ledge which leaves an opening at one end of the body through which molten metal may be poured, the beginning of the inclined lower surface of the cover which 45 forms an upper wall of the mold cavity being below the top of the opening similar to that of the first embodiment and for the same purpose.

Other objects and advantages of this invention will more fully appear from the following detailed description, taken in connection with the accompanying drawing, in which

Fig. 1 is a plan view of an ingot mold embodying the invention;

Fig. 2 is a side elevation thereof, partly in 55 section;

Fig. 3 is an enlarged vertical section taken on the line 3—3 of Fig. 2;

Fig. 4 is a side elevation, partly in section, of a modified form of the mold shown in Figs. 1, 2 and 3;

Fig. 5 is a fragmentary plan view thereof;

Fig. 6 is an enlarged vertical section taken on the line 6—6 of Fig. 4, and

Fig. 7 is a fragmentary side elevation, partly in section, of a modified form of the mold shown in Figs. 4, 5 and 6.

Referring now to the drawing in detail, particularly to Figs. 2 and 3, 10 is a horizontal integral body member, preferably of cast copper and having a mold cavity 11. Opposite side walls 12 of the body member 10 (Fig. 3) are tapered slightly inwardly from the upper portion to a bottom wall 13 thereof and portions of the bottom wall are inclined slightly upwardly adjacent each end wall 14 (Fig. 2) and the latter walls are inclined slightly outwardly, all for the purpose of facilitating the removal of the ingot cast in the mold. Formed in the upper inner edges of the side and end walls 12 and 14, respectively, are continuous depressed cover seating ledges 16. The ledges 16 begin at points 17 of portions 18 (Fig. 1) of the side walls at the center of the body member 10 and extend along one side wall 12, the end wall 14 and the opposite side wall 12, and are inclined downwardly from the points 17 to the end walls 14 for a purpose to be described hereinafter.

Mounted in the body member 10 and fitting closely against each of the ledges 16 are cover plates 20 made of copper, the lower surfaces of which form downwardly inclined upper wall portions for the mold cavity 11. The cover plates 20 are clamped against the ledges by means of steel clamping bars 21 extending transversely of the body member 10 and held in position by C-shaped clamping members 22 (Fig. 3) which at their upper ends engage opposite ends of the bars 21, the latter being spaced from the upper surface of the body member 10. At their lower ends the clamping members 22 are equipped with screws 23 which are threaded therethrough and into engagement with shoulders 24 extending longitudinally of the body member 10. Each of the cover plates 20 is provided with an eye 26 for facilitating the removal thereof from its seat 27 against the ledge 16. The cover plates 20 and the mounting thereof in the body member 10 in the above described manner results in an opening 27 between the adjacent ends of the covers at the points 17, through which opening the

molten metal is poured to form an ingot 28.

Due to the horizontal mold cavity 11 at either side of the opening 27 being inclined downwardly an effect similar to a vertical type of mold is obtained. In the vertical mold it will be apparent, due to the depth thereof, that an ingot having a maximum of density will be cast and one with smooth and uniform surfaces throughout, except for one end, which can be cropped off.

In a horizontal type mold with the mold cavity arranged in the manner herein described an increased density of the ingot will result and the shrinkage of the cast metal will occur in the metal between the top of the opening 27 and the beginning of the downwardly inclined upper wall portions of the mold cavity 11 provided by the lower surfaces of the cover plates 20, the latter occurring below the top of the opening. Any wrinkled and oxidized surfaces will thus be confined to this portion of the ingot at the opening 27 and a slight projection or protuberance 29 occurring at this point may be removed without impairing the strength or quality of the remaining portion of the ingot.

When casting, for example, deoxidized copper ingots wherein a greater volume of metal will be effected by shrinkage than can probably be accommodated in the projection of metal 29 between the top of the opening 27 and the beginning of the downwardly inclined upper wall portions of the mold cavity a modified form of body member and covers may be used. In this proposed form of mold the portions 18 of the side walls 12 of the body member 10 between the points 17 are extended upwardly and the inner adjacent ends of the cover plates 20 are provided with upwardly and transversely extending portions aligned at their upper ends with the upper ends of the side wall extensions. This arrangement, it will be apparent, will accommodate a greater volume of metal above the beginning of the downwardly inclined upper wall portions of the mold cavity than can be accommodated in the mold shown in Figs. 1, 2 and 3, and consequently will be able to absorb a greater amount of shrinkage without affecting the metal below the upper wall portions of the mold cavity.

In Figs. 4, 5 and 6 is illustrated another embodiment of this invention wherein a single continuous depressed cover seating ledge 30 is formed in the inner upper edges of side walls 31 and one end wall 32 of a horizontal integral body member 33 having a mold cavity 34. The ledge 30 begins at points 35 of the side walls 31 adjacent an end wall 36 and extends along one side wall 31, the end wall 32 and the opposite side wall 31 and is inclined downwardly from the points 35 for a purpose similar to that described in connection with the first embodiment. Fitting closely against the ledge 30 is an arched cover plate 37 provided with a longitudinally extending vertical rib 38 upon its upper surface, the arching of the cover and the rib serving to minimize distortion of the cover caused by repeated heating thereof and thereby reducing the formation of fins upon the cast ingots. The lower surface of the cover 37 forms a single inclined upper wall for the mold cavity 34. A bottom wall 39 of the mold cavity 34 has preferably an inclination similar to that of the lower surface of the cover plate 37, although it may be desirable in some instances to vary this inclination or it may be horizontally disposed.

The cover plate 37 may be secured in place against the ledge 30 in a manner similar to that disclosed in Figs. 1 to 3, inclusive. An opening 40 is formed between the end of the cover plate 37 at the points 35 and the end wall 36, through which opening the molten metal is poured to form an ingot 41.

In another form of this invention (Fig. 7) it is proposed to extend the body member 33, of the embodiment illustrated in Figs. 4, 5 and 6, at its right to provide a continuous single mold cavity 42 served by a single opening 43 for pouring the molten metal. The extended portion of the mold cavity 42 will be substantially complementary to the mold cavity 34, having a downwardly inclined lower wall beginning at the right side of the opening 43, which opening will be arranged intermediate the ends of the body member, the top of the opening being above the beginning of the inclined lower surfaces of a pair of covers 44 mounted against ledges in a manner similar to that of the hereinbefore described embodiment of the invention. The lower surfaces of the covers 44 will form the upper wall portions of the mold cavity 42. The bottom wall of the mold cavity may be inclined slightly upwardly at spaced points adjacent the center of the mold cavity and below the opening 43, similar to the inclined surfaces adjacent the outer ends of the body member. By means of this last described mold served by a single opening 43 for pouring the molten metal a single ingot may be cast, which may be severed at each side of the projection occurring across the opening between the covers 44 to provide two similar ingots of the quality provided by the previously described molds, and the section of metal formed by the severing will contain all the shrinkage of the two ingots. This type of mold will be particularly useful when casting copper ingots wherein a greater volume of metal will be effected by shrinkage, such as occurs in the casting of deoxidized copper ingots, in which case the section of metal extending from the top of the covers at the opening to the bottom wall of the mold cavity will be ample to absorb all shrinkage.

Although the invention as herein described and illustrated is particularly well adapted for casting copper wire bars, it will be understood that the invention is capable of other applications and that modifications can be made without departing from the spirit and scope of the appended claims.

What is claimed is:

1. A mold having a mold cavity and provided with downwardly inclined cover supporting surfaces extending from adjacent points between the ends of the cavity to the ends thereof, and covers supported thereon to form downwardly inclined spaced upper wall portions for the mold cavity.
2. A mold comprising a body member having a mold cavity, the walls of the member having downwardly inclined ledges extending therefrom around from opposite points adjacent the center of the cavity to the ends thereof, and cover members engaging the ledges to form downwardly inclined upper wall portions for the mold cavity at each side of the center thereof and an opening between the adjacent ends of the covers through which molten metal may be poured.
3. A mold comprising a horizontal body member having a mold cavity, vertical walls of the member having downwardly inclined surfaces at

their upper edges extending from points adjacent the center of the cavity to the ends thereof, and cover members engaging the said surfaces to form downwardly inclined spaced upper wall portions 5 for the mold cavity.

4. A mold comprising a body member having a mold cavity, the walls of the member having downwardly inclined surfaces extending from points adjacent the center of the cavity to the

ends thereof, and cover members engaging the said surfaces to form downwardly inclined spaced upper wall portions for the mold cavity with an opening between the adjacent ends of the covers through which molten metal may be poured, the top of the opening being above the beginning of the inclined wall portions. 80
